[57] CLAIM

The ornamental design for a cordless electrically heated cup, as shown and described.

DESCRIPTION

FIG. 1 is a top perspective view of a cordless electrically heated cup showing my new design;
FIG. 2 is a side elevational view thereof;
FIG. 3 is a top plan view thereof;
FIG. 4 is a bottom plan view thereof;
FIG. 5 is a left end elevational view of FIG. 2 of the bowl portion thereof;
FIG. 6 is a right end elevational view thereof of FIG. 2;
FIG. 7 is an exploded perspective view thereof;
FIG. 8 is a right end elevational view of FIG. 2 with the handle omitted for convenience of illustration; and
FIG. 9 is a bottom plan view thereof of FIG. 8.
